UNITED STATES PATENT OFFICE.

JOSEPH FARRIS, OF SPRINGFIELD, ILLINOIS.

FURNACE CONSTRUCTION.

1,410,664.

Specification of Letters Patent. Patented Mar. 28, 1922.

Application filed October 26, 1921. Serial No. 510,546.

To all whom it may concern:

Be it known that I, JOSEPH FARRIS, a citizen of the United States, residing at Springfield, in the county of Sangamon and State 5 of Illinois, have invented certain new and useful Improvements in Furnace Constructions, of which the following is a specification.

My invention pertains to new and useful 10 features of construction in furnaces, such as those of the hot air type used for heating dwellings; whereby the air passing through the furnace and being heated thereby will be adequately humidified and freed from 15 dust and particles of dirt.

A further or added purpose of the invention is the provision of a construction of this 20 general style which materially reduces or minimizes the loss of heat through the base or lower portion of the furnace structure, thereby increasing the operating efficiency of the appliance in material or substantial degree.

To the accomplishment of these and other 25 desirable ends, in the preferred embodiment of the invention a space is provided beneath the ash-pan and this space as well as the other portions of the furnace-base are adapted to accommodate a supply of water which 30 becomes somewhat heated by reason of its proximity to or contact with the bottom of the ash-pan and which delivers its heat thus derived and its moisture to the air flowing through the furnace adjacent to such water 35 supply, the latter in addition trapping or accumulating much of the dust of such air and hence preventing its passage into the dwelling rooms.

In order that those skilled in this art may 40 have a full and complete understanding of this invention and the various structural and functional benefits accruing therefrom, in the accompanying drawing, forming a part of this application and to which reference should be 45 had in connection with the following detailed description of the appliance, like reference characters have been used throughout the several views to indicate the same parts.

In this drawing:

50 Figure 1 is a horizontal section through the lower portion of the furnace structure; Figure 2 is a fragmentary central vertical section on line 2—2 of Figure 1;

55 Figure 3 is an enlarged fragmentary elevation of that portion of the appliance illus-

trating the overflow aperture and the drain plug; and

Figure 4 is a fragmentary vertical section on line 4—4 of Figure 3.

As is clearly depicted in the drawing, the 60 furnace appliance includes a horizontal, cast-metal, shallow, base-pan or tray 10 of general, but not exact, circular shape having a correspondingly-shaped, border or marginal, upstanding flange or rim 11 shouldered externally at 12, recessed at 13 for overflow, and provided with a screw-threaded drain-hole, normally closed or filled by a threaded plug 14 with an angular head by means of which it may be turned when necessary. 70

The front edge portion 15 of the flange 11 of such pan is straight instead of curved to provide for a flat front face for the furnace, and the top surface of the pan is supplied with two, spaced, upright, right-angle lugs 75 or bosses 16, 16 and associated or companion straight lugs or ears 17, 17.

These four complementary lugs are designed to hold against displacement a cast-metal bottom or floor member 18 of the ash-pan which is equipped with depending lugs or feet 19 and 20 resting on the base-pan in substantial register with the cooperating parts 16 and 17, thus holding the element 18 spaced above or supported from the base-pan a small distance so that the body of 80 humidifying or vapor-supplying water contained in the base-tray will be beneath and usually, but not necessarily, in contact with the bottom of member 18. 90

That part of element 18 inside of the base-pan is of general rectangular form with two front corners 22, 22 beveled off to fit the curvature of the rim or flange 11 at those points, and such part of member 18 inside of the 95 base-pan has a marginal upright flange 23 with its top edge above the water level in pan 10 as determined by the height of the overflow hole 13.

At the front straight part of the pan or 100 tray 10, the flange 23 of the floor member of the ash-pan is integral with a narrow, horizontal web 24, positioned directly over the top edge of flange 15, which merges into a vertical web 25 just outside of the flange 23, 105 and this in turn joins with a front, outstanding, horizontal platform or ledge 26 equipped with a supporting depending flange 27 along its front and two end edges.

From an understanding of this construc- 110

tion, it will be seen that the base-pan or tray rests on or is set into a suitable foundation, such as cement, and that the flange 27 is similarly supported by the same structure, the parts 23, 24 and 25 providing between them a suitable straight groove on the under side of the ash-pan member to receive the flange 15.

Thus this ash-pan floor-member is partly 10 inside of and partially outside of the base-pan, extending forwardly over the front flange of the latter and being especially formed or shaped for this purpose.

The companion, open-bottom, ash-pit member 28 rests on the floor element 18 just 15 inside of its retaining flange which holds it in place, extends forwardly over the parts 15, 23, 24, and 25, being provided at the front of the furnace with a suitable or appropriate hinged door 29, and is equipped 20 at its top with an appropriate grate 30 and fire-pot 31, although the grate operating mechanism has not been illustrated.

Furnace cement or any other suitable material 25 is employed at the joint between the parts 18 and 28 to render the same leak-proof or gas-tight.

A fitting or conformable furnace front-plate 32 straddles the front portion of the 30 ash-pan and is held in place on ledge 26 by buttons or bosses 33 on its top surface.

The outer shell or casing 34, as is usual, 35 is made of sheet-metal, its lower edge resting on the shoulder 12 of the flange or marginal rim of the base-pan, such casing or shell just above the water level in the base-pan having a suitable number of cold air intake flues or pipes 35 and 36, two in the present instance, although the exact number 40 is not material, a hole at its lower edge in register with the overflow aperture 13, and two doors 37, 37 at opposite sides of the furnace permitting the ready introduction of water into the bottom pan.

It will be perceived that the water level 45 is such, determined or fixed by the position of the overflow aperture, that the water is beneath and in contact with the bottom surface of the ash-pan floor member 18, hence 50 the water in large measure absorbs the heat which would otherwise be dissipated through the bottom of the furnace into the furnace room and gives up such heat in the form of warm vapor to the air entering through 55 the admission pipes 35 and 36, thus humidifying the air in adequate degree as it flows through and becomes heated by the furnace.

Such outer air is delivered into the furnace just above the surface of the water 60 and by reason of the proximity of the latter and the change of direction of air flow directly above it, a substantial quantity of the dirt and dust in the air is trapped and held by the water.

To clean out or flush this bottom water

pan, it is merely necessary to remove the drain-plug 14 and introduce water, as by means of a hose or otherwise, through either one of the doors 37 into the pan permitting it, together with the accumulated 70 dirt, to flow out through the drain hole.

The top edge of the flange of the ash-pan floor member being above the overflow aperture, there is no danger at any time of any of the water entering such ash-pan, the 75 overflow always acting as a suitable safety means.

Inasmuch as the two members of the ash-pan are sealed together gas-tight and extend forwardly beyond the shell or casing 80 of the furnace, where a gas-tight door is provided, the door and ash-pan having a ground joint, the former being held closed by a suitable handle, there is no danger of any leakage of gas from the ash-pan and 85 especially no leakage in such a manner as would contaminate the air being heated and humidified by this portion of the furnace.

The invention herein set forth in detail, 90 as will be understood by those skilled in the art, is susceptible of a variety of satisfactory embodiments and is not limited to the precise and exact details of construction of the one embodiment shown and described because in this appliance many changes may 95 be made without departure from the substance and essence of the invention and without the sacrifice of any of its substantial benefits and advantages.

I claim:

1. In an air heating furnace of the character described, the combination of a base-pan adapted to hold a body of humidifying water and having an upstanding marginal rim uninterrupted except by an overflow 105 aperture and a normally-closed drain-hole in such rim, an ash-pan having a floor member spaced above the bottom of said base-pan and of an area less than that of the body of water in said base-pan thereby exposing a 110 portion of the surface of such water outside of said ash-pan, said ash-pan extending forwardly over and beyond the rim of the base-pan at the front thereof, said floor member having a marginal flange the top edge of 115 which is above the water level determined by said overflow aperture, an enclosing casing for the furnace, means permitting the delivery of water into such base-pan, and means to admit the air to be heated into said 120 casing above the water in said base-pan, said overflow aperture being positioned at such height as to permit the water in the base-pan to contact with the bottom face of 125 said ash-pan floor member.

2. In an air heating furnace of the character described, the combination of a base-pan adapted to hold a body of humidifying water and having an upstanding marginal rim uninterrupted except by an overflow 130

aperture, an ash-pan supported by said base-pan and having a floor member the bottom face of which is spaced above the bottom of said base-pan at a height below the lower 5 edge of said overflow aperture thereby permitting said body of water to contact with the bottom face of said floor member, said ash-pan being of less area than that of the body of water in said base-pan hence exposing a portion of the surface of such water outside of said ash-pan, said ash-pan extending forwardly over and beyond the rim of the base-pan at the front thereof, said ash-pan floor member having a marginal up- 10 standing flange the top edge of which is above the level of the water in the base-pan determined by said overflow aperture, an enclosing casing for the furnace supported on said base-pan, means to deliver water into 15 said base-pan, and means to admit air to be heated into said casing above said water.

3. In an air heating furnace of the character described, the combination of a base pan adapted to hold a body of humidifying water equipped with means to limit the maximum height of the water therein, an ash-pan above said base-pan having a floor member spaced above the bottom of the base-pan thereby permitting a portion of the 20 body of water to reside beneath and in contact with the bottom face of such floor member, said floor member having an upstand-

ing marginal flange the top edge of which is above said maximum water level, an enclosing furnace casing, means permitting the 35 introduction of water into said base-pan, and means to admit air to be heated to said furnace casing in proximity to said body of water.

4. In an air heating furnace of the character described, the combination of a base-pan adapted to hold a body of humidifying water equipped with means to limit the height of water therein and with means to drain the water therefrom, an ash-pan above 45 said base-pan having its floor spaced upwardly away from the bottom of said base-pan permitting at least a portion of the water to reside beneath and in contact with the bottom of the ash-pan, a casing for the 50 furnace, a door in said casing giving access to said base-pan, and means to admit air to said casing in proximity to said body of water.

5. In an air heating furnace of the character described, the combination of an ash-pan, means to hold a body of air-humidifying water in part beneath and in contact with the bottom of said ash-pan, and means to cause the incoming air to flow in proximity to the exposed surface of said body of water to become humidified thereby. 55 60

JOSEPH FARRIS.
